ATTORNEYS

UNITED STATES PATENT OFFICE.

JAMES WELLS MUNN, OF CHICAGO, ILLINOIS.

CARD-INSCRIBING DEVICE.

Application filed March 27, 1924. Serial No. 702,470.

My invention relates to improvements in card inscribing devices, particularly that type of device employed for writing advertising cards and show cards with sealing wax or the like, and it consists in the combinations, constructions, and arrangements herein described and claimed.

An object of my invention is to provide a device of the character described by means of which an inscription may be made upon the card, and having the appearance of embossing.

A further object of my invention is to provide a card inscribing device of the character described in which novel means is employed for supplying a melted wax to the writing tip.

A further object of my invention is to provide a card inscribing device of the character described in which the sealing wax or other material employed may be introduced in the solid stick form and which possesses the feature of automatically feeding the wax to the heating element as it is needed.

A further object of my invention is to provide a card inscribing device of the character described which is provided with a plurality of removable writing tips, each being capable of forming lines of a predetermined character.

Other objects and advantages will appear in the following specification, and the novel features of the invention will be particularly pointed out in the appended claims.

My invention is illustrated in the accompanying drawings forming part of this application, in which—

Figure 1 is a side elevation of an embodiment of my invention, in an operative position;

Figure 2 is an enlarged view of the mechanism illustrated in Figure 1 partially in section;

Figure 3 is a perspective enlarged view of one of the writing tips;

Figure 4 is an enlarged perspective view of another writing tip; and

Figure 5 is an enlarged perspective view of still another writing tip.

In carrying out my invention I make use of a fiber tubular member 1 having each end thereof open so that the stick of sealing wax 2 may be introduced thereto and one end of the wax permitted to protrude through the end of the tube. This tubular member 1 is truncated at its lower end as shown at 3.

A metal cylinder 4 containing an electric heating element 5 is secured rigidly to the fiber tubular member 1 by means of a rigid metal bracket 6 secured to the cylinder 4 by means of a machine screw 7. I have shown in Figure 1 the relative positions of the members 1 and 4 to one another. The cylinder 4 should be substantially upright when the tubular member 1 is in the natural position of a pencil when in the hand of the person writing therewith.

Electric feed wires 8 protected by a flexible cable casing 9 are connected with a heating element 5 so that electric current may pass through the feed wires 8 and cause the heating element 5 to operate and heat the metal cylinder 4. The lower portion of the cylinder 4 is tapered as shown at 10 and terminates in a removable tip 11 which I shall hereinafter refer to as a writing tip.

One of the tips 11 is shown in Figure 3 and is substantially rectangular at its work engaging face as shown at 12. This particular tip is employed for inscribing lines of varying breadths therewith. The breadth of the line is determined by the angle at which the tip 11 is placed as the tip is drawn across the card as shown at 13.

A coil of copper wire 14 is secured adjacent the side wall of the cylinder 4 and in registration with the truncated end 3 of the tubular member 1 by means of a screw 15. This coil 14 is of the shape commonly referred to as a pancake coil. The wire 16 is secured at one end to the screw 15 adjacent the coil 14 and at its opposite end to the bracket 6 intermediate its length as shown at 17.

From the foregoing description of the various parts of the device, the operation thereof may be readily understood. Let us

assume that it is desired to produce an inscription upon the card in which the lines of the inscription are of varying breadth and that the inscription must be done in some substance such as sealing wax having a hard finish when in normal condition. A stick of the sealing wax 2 is dropped into the fiber tube 1, whereupon the sealing wax 2 will assume the position shown in Figure 2, i. e., the lower end thereof will contact with the wire 16 adjacent to the coil 14. Current is then permitted to flow through the heating element 5 by means of the feed wires 8 so that the cylinder 4 may become heated. When the cylinder 4 is sufficiently hot to convey heat by conduction through the coil 14 and to the wire 16, the wax immediately adjacent the wire 16 and the coil 14 will melt and will flow freely in limited quantities upon the outer wall of the cylinder 4, where it will seek its lowest level upon the card 13 as shown at 18. The device is grasped manually by means of the fiber tubular member 1 and manipulated in precisely the same manner as a brush or pen commonly used for the inscription of legends upon cards or the like. In the present instance the tip 11 having a rectangular work engaging surface 12 should be employed, so that the lines may be of varying width at the will of the artist, and substantially flat and close to the card.

If, however, it is desired to form an inscription in which the lines have the appearance of embossing performed by an embossing process, it is necessary to substitute the tip 11 in Figure 4 having a work engaging surface 19 that is provided with a recess extending longitudinally thereof. When this tip is employed the wax will be virtually molded as it contacts with the cool papers 13, and harden in the form of an up-standing ridge, having much the same appearance as though the inscription were made by an embossing process in which the card is actually pressed upwardly.

One of the important features of my improved card inscribing device is that the wax does not come into contact with a flame of any kind, since the melting of the wax is accomplished by means of an electric heating element encased completely in the cylinder 4. It is therefore impossible for the wax to burn or to become volatilized through excessive heat. It should also be noted that only a limited quantity of the wax is in contact with the heat conducting elements of the device, so that therefore but a limited quantity of melted wax is permitted to flow upon the surface of the cylinder 4.

In Figure 5 I have shown still another modified form of the writing tip 11. This form is provided with a pointed tip 21 and may be used wherever it is desired to have a

line of uniform breadth and relatively thin as might be made by the use of the ordinary type of inking pen. It should be noted that many modifications of the writing tip may be employed without departing from the spirit and scope of my invention, and the nature of the writing tips may be determined more fully by the requirements which may arise from time to time for inscriptions of the particular nature.

It should be further noted that the use of my invention is not limited to the preparation of show cards and inscriptions, but may also be employed quite successfully for decorating objects as in the case of a frieze or the like upon a picture frame.

I claim:

1. A card inscribing device of the type described comprising a writing tip, a cylinder for removably supporting said writing tip in an operative position, a heat producing element disposed in said cylinder, a second heat producing element secured to the outside of said cylinder, and heated by conduction from said first named element, and means for supporting a normally solid meltable substance in close proximity to said elements, whereby the heat from said heat producing elements is adapted to melt the portion of said substance contacting therewith to cause the substance to flow in a liquid state to said point.

2. A device of the type described comprising an inscribing member, means for heating said member, and a casing removed from said member for carrying a meltable substance and for holding this substance in contact with the inscribing member, whereby only that portion of the substance touching the heated inscribing member will be melted, thus permitting the main body of the substance to be removed at will.

3. A card inscribing device of the type described comprising a writing tip, a cylinder for removably supporting said tip, a heat producing element disposed in said cylinder, and a tubular member mounted adjacent to said cylinder and having one end substantially in registration with the side of said cylinder, said tubular member being arranged to permit the introduction of a bar of normally solid meltable material, whereby said substance may slide into close proximity with said cylinder and be melted from the heat of said heating element, whereby said substance may flow in a liquid state to said writing tip.

4. A device of the type described comprising an inscribing member, means for heating said member, and a casing removed from said member for carrying a meltable substance and for holding this substance in contact with the inscribing member, whereby only that portion of the substance touching the heated inscribing member will be melted,

thus permitting the main body of the substance to be removed at will, said casing being inclined so as to feed the meltable substance by gravity to the inscribing member as needed.

5. A device of the type described comprising a solid inscribing member, means re-

moved from said inscribing member for carrying a meltable substance and for feeding this meltable substance to the exterior surface of the inscribing member, whereby the inscribing member may be readily cleaned after use. 10
